UNITED STATES PATENT OFFICE.

ISAAC DEMUTH, OF NEW YORK, N. Y.

DESIGN FOR A SMOKING-PIPE.

Specification forming part of Design No. 7,987, dated January 5, 1875; application filed December 17, 1874.
[Term of Patent 7 years.]

To all whom it may concern:

Be it known that I, ISAAC DEMUTH, of the city, county, and State of New York, have invented a Design for Smoking-Pipe, of which the following is a specification:

This invention is illustrated in the accompanying drawing, in which—

Figure 1 represents a side view. Fig. 2 is a front view.

Similar letters indicate corresponding parts.

This design consists in a smoking-pipe the bowl of which has the form of a coffin.

In the drawing, the letter A designates the

coffin-shaped bowl of my smoking-pipe, and B is its stem.

What I claim as new, and desire to secure by Letters Patent, is—

The design for a smoking-pipe, as shown and described.

In testimony that I claim the foregoing I have hereunto set my hand and seal this 10th day of December, 1874.
